UNITED STATES PATENT OFFICE.

JESSE B. GARBER, OF SALEM, OHIO, ASSIGNOR TO THE DEMING COMPANY, OF SALEM, OHIO, A CORPORATION OF OHIO.

PUMP.

Application filed July 13, 1922. Serial No. 574,648.

To all whom it may concern:

Be it known that I, JESSE B. GARBER, a citizen of the United States, residing at Salem, in the county of Columbiana and 5 State of Ohio, have invented a certain new and useful Improvement in a Pump, of which the following is a full, clear, and exact description, reference being had to the accompanying drawings.

10 This invention relates to reciprocating pumps of the type adapted to operate upon movement of the piston in both directions.

The objects include the provision of a 15 simple, efficient construction, capable of being cheaply manufactured and durable and efficient in use. The present invention is particularly concerned with the construction of such pump adapted to be hand-operated, and one of the objects is to provide 20 a self-contained structure in which an air chamber surrounds the piston, the whole forming a compact unit.

More specific objects include the design 25 of the parts so that they may be conveniently assembled and whereby leakage, either of water or air from the compression chamber, is prevented. For example, a stuffing box cap surrounding the piston, and acting in its normal capacity as a seal, has 30 an extension projecting below the normal level of the water to further act as a water seal against the escape of air, is so arranged that when it be removed it permits removal of the piston, cylinder and associated parts 35 from the pump casing.

The means for carrying out my invention 40 will be more fully set forth in the following description which pertains to the accompanying drawings, and the essential features will be summarized in the claims.

In the drawings, Fig. 1 is a vertical section through a pump constructed according 45 to my invention; Fig. 2 is a side elevation of the pump on a reduced scale; Figs. 3 and 4 are elevations of the upper and lower cages removed from the pump; Figs. 5 to 9, inclusive, are sections taken on the lines 5—5 to 9—9 respectively.

50 My invention is directed, in general, to the provision of a force pump wherein the water raised from a well or receptacle is caused to flow into an air compression reservoir formed between the pump casing and the cylinder wall, whereby a steady flow of water may be obtained. Accordingly, in the

various figures, I have shown the pump as embodied in a casing 10, with a cylinder or shell 11 mounted therein, and a piston 12 which is adapted to reciprocate within the cylinder. Suitable inlet and outlet valves, 60 indicated at 13 and 14, are disposed vertically with relation to each other, whereby gravity assists in closing the valves. A piston operating handle 15 is shown as fulcrumed on a standard 16, which in turn may 65 be carried by the pump casing or by a base 17, as shown in Fig. 1. The details of the construction will now be described.

The casing 10 may be a hollow casting having inturned flanges or heads 20 and 21 70 provided with openings to receive the piston cylinder 11. The upper interior portion of the reservoir is larger in cross sectional area than the bottom portion, forming an air and water chamber, effecting a 75 steady flow of water through an outlet 22 at or near the lower end of the chamber. A discharge connection 23 is shown attached to the outlet 22.

The shell or cylinder 11 may be a seamless 80 tube having its ends thereof internally threaded, and having a smooth exterior which closely fits within complementary openings in the upper and lower heads of the casing. The cylinder is secured in position by members 25 and 26 in the nature of flanged collars presenting angular portions whereby they may be conveniently turned to cause a screw threaded portion to engage the internal threads of the cylindrical member 11, while the flanges overhang 85 the adjacent head portions of the casing and serve to position the cylinder, and at the same time clamp upon gaskets 27 and 28. 90

The upper member 25 is so formed that 95 it may serve as a stuffing box for the tubular piston 31, it being provided with packing compressed by a collar 30 moved inwardly by an internally threaded head or nut, as shown. The lower end of the member 100 25 is provided with an extension reduced below the diameter of the threads, engaging the cylindrical tube, to allow water to pass through the openings 29 from the interior of the cylinder to the casing, and at the same 105 time this extension 25a projects below the lower sides of these openings and thus below the normal water level, forming a water seal.

The lower clamping member 26 is pro- 110

vided with an upper extension forming a ball valve cage, designated 34, while having an inwardly projecting valve seat 35 for the valve ball 13. The intake pipe 36 is 5 threaded into a downward extension of this same member 26. The convenience of this unity of structure in the one member 26 will be apparent, as the construction and machine work, on this part, consist of simple operations; yet it functions as a clamping member for the cylinder; there is a 10 threaded extension for the intake, and a mounting for the inlet valve, which make for convenience and simplicity. This member, it will be seen, being hollow, forms an inlet passage for the water to pass this valve ball into the lower end of the cylinder. A pin 37 extending across the upper portion of the valve cage may retain the valve 15 ball 13.

The member 26 may be threaded into the cylinder, before the cylinder is inserted within the casing, and then locked against rotation relatively to the casing by a projection 38 carried thereby. This projection may be placed between lugs 39 extending downwardly from the lower portion of the casing, as shown particularly in Fig. 9. In this way, the pump may be assembled 25 by inserting the cylinder from the bottom of the casing and then locking it against the top thereof by means of a locking member 25. A further purpose for this lock indicated at 38 and 39 is, that the pump when 30 once assembled, may be readily threaded onto a conduit 36 without unthreading the member 26 from the interior of the cylinder.

The means 15 for operating the pump 40 may be embodied in a handle 15 one end of which is pivoted, as at 40 to a yoke 41, which is adapted to be rigidly attached to the outer end of the piston 12.

The fulcrum for the handle is indicated 45 at 42 as being a pin connection which is supported by the bracket 16. The lever may have a series of openings as at 43 for engaging the fulcrum pin 42 and the bracket may be pivoted, as at 44, for permitting the piston to be adjusted to the convenience of the user.

The bracket 16 preferably comprises a single strip of metal formed in such manner that the ends thereof are pivotally supported on the connection 44 while the intermediate portion forms a support which straddles the lever and carries a fulcrum pin 42. The manner of connecting the ends of the bracket to the support therefor, is 55 embodied in a set of oppositely disposed lugs 45 on a base 46. The base is shown as having an upstanding flange 47 which surrounds the lower part of the casing and serves as a support therefor. A suitable 60 clamping screw 48 may be used with the 65

discharge at any suitable angle for locking the base to the casing with relation to the handle.

The operation of a pump constructed in accordance with my invention is as follows:—

Assuming that the various parts are assembled as shown in Fig. 1, then when the piston 12 is forced upwardly by the operator, the valve 14 is held by gravity against the seat 32 while the valve 13 is drawn away from its seat by the action of the piston on the suction stroke. When the upward motion of the piston is stopped, the weight of the water, drawn into the cylinder forces the valve 13 to the seat 35, thus trapping the water within the cylinder. Then as the piston is forced downwardly, the entrapped water pushes the valve 14 upwardly, whereupon the water flows 75 through the openings in the cage 31 into the space above the valve 14 and between the piston 12 and cylinder 11, passing through the openings 29 and into the casing 10. Then when the downward motion of the piston is stopped, the valve 14 engages the seat 32, thus trapping water between the valve and the top of the cylinder. On the next suction stroke, the water above the valve 14 is lifted, and is caused to pass through 80 the openings 29 and into the casing 10. On the following discharge stroke, then, the water trapped between the valves 13 and 14 passes into the cylinder and above the valve 14 as before. It follows then, that 85 on each reciprocation, water is flowing from the cylinder into the air chamber formed in the casing 10.

In view of the foregoing description, it 90 will be seen that a pump constructed in accordance with my invention embodies few working parts, and employs valves which are so arranged that a quick seating action 95 may be obtained. Furthermore, the relation between the cylinder and pump casing 100 is such, that a discharge head under air pressure may be maintained in the casing to provide a uniform flow. The arrangement of the parts is such that with the air chamber surrounding the piston a comparatively short pump is provided, while the water passages are easily made and are very direct. The extension on the stuffing box member provides a water seal so that leakage of air from the air chamber is prevented 105 without requiring an air tight fit in this stuffing box. The parts are very accessible, as removal of the stuffing box cap allows removal of the operating elements.

Having thus described my invention, I claim:—

1. A pump comprising, in combination, a hollow cylinder having the ends thereof internally threaded, a casing surrounding 110

- the cylinder and of substantially the same length as the cylinder and having openings in the ends thereof into which the cylinder extends, closure members in threaded engagement with the cylinder at each end thereof, each of said members functioning to connect the cylinder to the casing, there being an opening through the wall of the cylinder into the casing whereby the latter 5 may act as a reservoir, a piston within the cylinder, a piston rod extending through one of said closure members, and a stuffing box surrounding said rod and associated with the last mentioned closure member 10 outside of the casing. 15
2. In combination, a cylinder, a piston therein, a casing surrounding the cylinder and providing a liquid reservoir, and an air chamber therefor, a passageway in the wall 20 of the cylinder adjacent the top thereof, and a member for sealing the cylinder to the casing, said member having a depending portion surrounding the piston and projecting into the cylinder and extending below said 25 passageway, whereby a water seal is provided to prevent the flow of air from said chamber, and a stuffing box outside said cylinder. 30
3. In combination, a cylinder, a piston therein, a casing surrounding the cylinder and providing a liquid reservoir, and an air chamber therefor, a passageway in the wall of the cylinder adjacent the top thereof, whereby the liquid to be pumped is caused to 35 rise within the cylinder and then to flow into the casing, a stuffing box member surrounding the piston outside the cylinder and casing and projecting into the cylinder below the water level therein, whereby a water seal 40 is provided to prevent the flow of air from said chamber. 45
4. A pump comprising in combination, a cylinder having the ends thereof internally threaded, a casing of substantially the same length as the cylinder, said casing having an opening in each end thereof through which the cylinder extends, upper and lower members in threaded engagement with the cylinder for clamping the casing thereto, the lower member having provision for receiving a conduit and having a ball cage integral therewith, a passageway through the cylinder adjacent the top thereof for permitting communication between the cylinder and casing, the upper member having a portion thereof extending downwardly into the cylinder below the passageway, a piston rod extending through the upper member, a piston 50 mounted on said rod within the cylinder, a stuffing box associated with the upper member outside the casing, and means for reciprocating the piston. 55
5. In combination, a vertically disposed cylinder, a piston reciprocable therein, an inlet valve mounted in the cylinder, an outlet valve mounted on the piston, a casing surrounding the cylinder, a passageway from the cylinder into the casing, an outlet from the casing, a mounting member surrounding the casing below the outlet, a pump handle attached to the piston, and means carried by the member for providing a fulcrum to the handle, whereby the piston may be moved in a straight line when the handle 60 is oscillated on the fulcrum therefor. 65
6. A pump having in combination, a cylinder, a piston reciprocable therein, a casing embracing the cylinder and terminating adjacent the ends thereof, locking members in threaded engagement with the inner wall of the cylinder for providing a fluid-tight connection between the cylinder and casing, a stuffing box outside the cylinder and associated with one of said members, an inlet valve associated with the other of said members, an outlet valve carried by the piston, and means whereby the liquid to be raised is caused to flow to the top of the cylinder, and then into the casing, and a discharge conduit 70 connected to the casing adjacent the lower portion thereof. 75
7. In combination, a vertically disposed cylinder, a piston reciprocable therein, a casing having an enlarged upper portion and a restricted lower portion, removable members in engagement with the ends of the cylinder for providing a fluid-tight connection between the cylinder and casing, one of said members embracing the piston, and the other of said members comprising a valve cage, a ball valve therein, another valve cage carried by the piston, a ball valve in the last mentioned cage, said valves being disposed 80 one above the other, a passageway leading from the interior of the cylinder to the interior of the casing and adjacent the top of the cylinder, a discharge conduit leading from the casing adjacent the lower portion thereof, whereby liquid raised by the piston is caused to move to the top of the cylinder, and then into the casing adjacent the enlarged portion, then through the restricted portion, and out the discharge conduit. 85
8. In combination, a vertically disposed cylinder, a piston reciprocable therein, a casing having an enlarged upper portion and a lower portion, means for providing a fluid-tight connection between the cylinder and casing, a valve cage carried by the cylinder, another valve cage carried by the piston, a ball valve in each of said cages, said valves being disposed one above the other, a passageway leading from the interior of the cylinder to the interior of the casing and adjacent the top of the cylinder, a discharge conduit leading from the casing adjacent the lower portion thereof, whereby liquid raised by the piston is caused to move 90 95 100 105 110 115 120 125 130

to the top of the cylinder, then into the casting adjacent the enlarged portion, then through the restricted portion and out the discharge conduit, a pump handle having one end thereof pivotally connected to the piston, and means for providing a fulcrum for the handle intermediate the ends there-

of, said means comprising a bracket pivotally supported adjacent the bottom of the casing.

10 In testimony whereof, I hereunto affix my signature.

JESSE B. GARBER.
